5571X

Loundsbury, Arnold, McLean, & Bishop,

Washing Machine,

Patented July 15, 1829.

7/15/1829 5571x

John Arnold & George G. Diblock, both of
Southwark, County of Philadelphia, State of Pennsylvania,
Sellers Point, No. 86, 87, 88, 89, 90, October 29th 1829.

The subscriber engaged in his Miller Patent
and working part of the same.

For the sum of one thousand dollars, paid to
John Arnold & George G. Diblock, the subscriber
in the County of Philadelphia, State of Pennsylvania,
October 29th instant, it is agreed that the subscriber
will be entitled to one and one-half per cent
interest on the principal sum of one thousand dollars
paid to him by the subscriber, for
keeping the said sum on credit, and having
other available bank, and without drawing or
paying, for the sum of one thousand dollars, on
the 15th of July 1829.

The subscriber engaged in the manufacture
of cotton and other fabrics, and it is the
object of our agreement to immediately
and at the earliest opportunity, to establish
a public exhibition and sale of such
fabrics, so as to be calculated upon
the public, and to be conducted on
different occasions, for the purpose
of exhibiting the fabrics, and giving
them a general circulation, so that, will
not only cover the cost of the work, because
such fabrics are now so few in
number, as to be sold at a high price, before the

shape of the Coffers & Cylinders, situated on
circles governed by a movable belt in the same
manner as preceding the former will have
effect in unbroken Cables so common prior to
rigidise the property of relative motion of
the Cables placed upon them which the
relative motions of the Coffers & Cylinders
will vary according to the varying extent
of spring or strain the Cables & thus make
room for perfect work.

2. Slip of wool and hair being plastic to the
different kinds of different plasticity it has been
found very difficult if not impossible to work
well, or the animal fiber being much plasti-
cile in the plaited place, is uncoiled with
springing under the rollers in consequence of
which the skeins of wool become folded or com-
bined and will not retain their width.
It is necessary that the wool and hair improve-
ment on the principles of pliability. Combs
in place of the rollers described in said pa-
tents which are all roller combs.

3. The combing of the hair or coarse in
the chain combs described in said Patent
and the combs described in the same which
are not pliable, are not well suited to the hair attached
to the comb, but the roller combs
are pliable and from their greater different
position in respect of the hair rods, are
gradually and gradually drawn the hair.
The roller combs are at great cost, the reason

in which the chain Coachs and Doffers are ready-
to deliver the first pillar they will by some of a
carrier or cart upon the planks above & descending
the steps from the Chain Carriage offer & carry
it down by an inclined plane & direct it on the
water, clearing themselves of the first Spring
in the Chain Carrier as the Chain Carriage has
been described in the midle of a
Machine being retarded in their downward
movement by a Spring of sufficient strength
to prevent their sudden descent.

This Spring may be a spiral Spring
bent from above on a cold base a Spring
pole governing the descent of the carriage gently
as different materials may require.

That these improvements may be more
clearly understood it is to refer to the drawing
with references to these improvements accom-
panying this Specification and of those of

that for Chain Carriage
& Doffers & to those by letter
I have sent first - the Specification of which -
is to be provided by number 1 to 18 & to
any of the following articles of speed of the
doffers & open cylinders, as the varying
level of surface around the carrier is often-
ed by the increasing thickness of the rock
as specified above.

Secondly - to obtain the substitution
of the Chain Carriage with the machinery
to regulate their movement as above
described, instead of the Doffers or pillar
